COMBINED ROOM DIVIDER AND CLOSABLE BAR

Maurice L. Lorge, 12167 69th Ave.,
Seminole, Fla. 33540

Filed Aug. 24, 1973, Ser. No. 391,218

Term of patent 14 years

Int. Cl. D6—04

U.S. Cl. D6—144

FIG. 1 is a front perspective of the combined room divider and closable bar showing my new design.

FIG. 2 is a reduced scale view in side elevation thereof shown in closed position and taken from the right of FIG. 1.

FIG. 3 is a reduced scale left front elevational view thereof shown in closed position.

FIG. 4 is a reduced scale top plan view thereof in open position.

FIG. 5 is a reduced scale bottom plan view thereof in open position.

FIG. 6 is a reduced scale rear elevational view thereof in open position.

FIG. 7 is a reduced scale top plan view thereof in closed position.

FIG. 8 is a reduced scale front elevational view thereof in closed position.

FIG. 9 is a reduced scale rear elevational view thereof in closed position.

I claim:

The ornamental design for a combined room divider and closable bar, as shown.
